GUARD MOUNTING FOR JOINTER CUTTERS

William E. Boice, Toledo, Ohio, assignor to Boice-Crane Company, Toledo, Ohio, a corporation of Ohio

Application December 30, 1950, Serial No. 203,596

2 Claims. (Cl. 144—251)

1

This invention relates to woodworking machines but more particularly to knife guards for jointers or the like, which serve as a safety feature to protect the operator from injury during the operation of the machine.

It is a desideratum to provide machines of this character with a jointer guard, which is efficient and satisfactory for the purpose intended but which can be readily and conveniently moved out of the way when desired without the necessity of disconnecting it from the machine, the guard being thus disposed in an out of the way position but conveniently located so that it can be almost instantaneously returned to its operative protective position.

An object is to produce a new and improved jointer guard mounting, which is not only inexpensive to manufacture and assemble but can be almost instantaneously moved to and from operative position and when in inoperative position likewise is positioned alongside of the machine occupying a minimum amount of space without interfering with the free and unrestricted use of the machine for rabbeting and other purposes.

Other objects and advantages of the invention will hereinafter appear and for purposes of illustration but not of limitation, an embodiment of the invention is shown in the accompanying drawings in which

Figure 1 is a front perspective view of a jointer showing the knife guard in position of use in full lines and showing it in its inoperative or out of the way position by broken lines;

Figure 2 is an enlarged top plan view of the guard, a fragment of the work table being shown to illustrate the mounting of the guard;

Figure 3 is a side elevation of the guard and associated work table fragment;

Figure 4 is a sectional view on the line 4—4 of Figure 2 showing the pivotal connection between the guard plate and the arm;

Figure 5 is a fragmentary end elevation of the hinged connected members, and showing a portion of the guard plate and the wing nut for securing the shouldered end of the guard carrying arm; and

Figure 6 is a fragmentary plan view of the guard in its inoperative position.

The illustrated embodiment of the invention comprises a jointer which has a cabinet base or standard 10, which elevates the jointer bed 11 having a flat table top 12. Adjustable on the bed 11 is a base 13a having a table 13 provided with longitudinal extension 13b. The base 13a is adjustable vertically relative to the table 12 by the

operation of hand wheel 14 as will be readily understood by those skilled in this art.

Shiftable transversely of the table tops and adjustable angularly is a fence 15, which can be secured in adjusted position by suitable fastening elements 16. A rotary cutter 17 extends transversely of the inner end portion of the table 13 and may be driven by an electric motor (not shown) arranged within the cabinet base 10.

For guarding the cutter 17 is a substantially flat metallic plate 18 generally triangular in shape which is pivotally connected to one end of a rod arm 19 so as to move relatively thereto transversely across the table top. As shown, one apex 15 of the plate 18 has a depending boss 20, which fits into a cup-shaped member 21 and a shouldered screw 22 provides a bearing about which the plate can rock. The guard plate has a depending hub-like portion 20a which bears against and rocks upon the flat top of the cup. The bottom of the cup 21 rests upon the top of the table 13.

Disposed in a cavity in the cup member 21 is a torsional spring 23, opposite ends of which are secured to the hub 20a and cup 21, the arrangement being such that the guard plate 18 is normally resiliently urged in a direction toward the fence 15, thereby to bear against the fence or a wooden work piece resting alongside the fence, as will be readily understood. The cup 21 has an opening on one side to receive the rod or guard arm 19, the end of which is in screw-threaded engagement with the opening.

The rod arm 19 extends at right angles to the axis of the guard plate 18 and in parallel relation slightly above the table 13. As shown, the rod arm extends a short distance beyond the end of the table extension 13b. The outer end portion of the guard arm 19 is shouldered to provide a reduced screw-threaded end 24 which extends freely through an aperture formed in an upright hinge member 25, the upper end of which is offset outwardly as indicated on Figure 5. On the outer end of the screw-threaded end portion 24 is a wing nut 26, which when loosened, enables the guard arm 19 to be turned or rocked as will hereinafter appear. The lower end of the hinge member 25 fits a yoke-like bracket 27, which is rigidly secured against a wall portion 13c, rigid with the under side of the table extension 13b by a bolt and nut assembly 28. A pin 29 pivotally or hingedly connects the bracket member 27 and hinge member 25 providing an axis for the hinge member 25 at right angles to the axis of the guard plate 18.

When the guard plate 18 is in its useful or operative position, it is disposed in the position shown by full lines on Figure 1 with the hinge member 25 upstanding, the torsion spring 23 resiliently urging the guard plate toward the fence 15. When it is desired to use the jointer for rabbeting purposes, for example, the guard plate 18 and its arm 19 are swung in a counterclockwise direction (Figure 1) about the hinge pin 29, and then by loosening the wing nut 26, the arm 19 can be turned sufficiently so that the guard plate can assume a depending position alongside of the bed 11 below the table top 12 and in inwardly spaced relation to the outer edge portion of the table extension 13b. In this position, the guard plate is out of the way and in a position, which does not interfere with the full and unrestricted use of the table tops and the rotary cutter 17. Thus the hinged bracket arm 25 swings from its uppermost position such as shown on Figure 3 to a depending position abutting against the wall portion 13c, thus supporting the guard plate in the desired position out of use and away from the operator. The guard plate 18 has a depending flange 18a, which spaces the plate a sufficient distance above the table 13 to clear the rotary cutter. This flange acts as a stop and engages the guard arm 19 when in inoperative position to retain the guard plate in the broken line position of Figure 1. Manifestly by reversing the above operation, the guard plate can be reinstalled quickly and conveniently in position of use.

The above structure can be inexpensively manufactured and assembled, the number of parts being reduced to a minimum. An important advantage resides in maintaining the guard plate connected to the machine at all times either in operative or inoperative position so that it is not mislaid or damaged but is at all times conveniently accessible for return movement to its operative position.

It is to be understood that numerous changes in details of construction, arrangement and operation may be effected without departing from the spirit of the invention especially as defined in the appended claims.

What I claim is:

1. In a jointer, an elongate table having contiguous relatively wide and narrow longitudinal portions, the relatively wide portion extending laterally from the narrow portion and having an inwardly extending shoulder at the end thereof adjacent the narrow portion, whereby said shoulder and the adjacent edge of the narrow portion define two sides of a pocket along one side of the

50 55

table for part of the length thereof; a knife mechanism mounted in the wide portion of the table; a knife guard; and a support for said knife guard mounted on said table, said support comprising a horizontal pivot affixed to said shoulder and extending transverse of the length of the table; an extension arm having one end swingably supported by said pivot; and a rotatable connection between the other end of said arm and said guard, the guard and support therefor being shorter in their maximum total dimensions, than said pocket whereby said guard and arm may be swung about said pivot between a working position adjacent said knife to a retracted position in which said guard rests entirely with said pocket.

2. In a jointer, an elongate table having contiguous relatively wide and narrow longitudinal portions, the relatively wide portion extending laterally from the narrow portion and having an inwardly extending shoulder at the end thereof adjacent the narrow portions, whereby said shoulder and the adjacent edge of the narrow portion define two sides of a pocket along one side of the table for part of the length thereof; a knife mechanism mounted in the wide portion of the table; a knife guard; and a pivotal support for said knife guard mounted on said shoulder, said support comprising a first bracket affixed to said shoulder, a pivot pin carried by said bracket and extending transversely of the length of said table, a second bracket having an ear pivotally supported on said pivot pin and a socket extending transversely of said pivot pin; an extension arm having one end rotatably supported in said socket; and a rotatable connection between the other end of said arm and said guard, whereby said guard and arm may be swung about said support between a working position adjacent said knife to a retracted position in which said guard rests in said pocket.

WILLIAM B. BOICE.
